UNITED STATES PATENT OFFICE.

WILLIAM H. JENKINS, OF PHILADELPHIA, PENNSYLVANIA.

MINING-DRILL.

SPECIFICATION forming part of Letters Patent No. 396,875, dated January 29, 1889.

Application filed August 22, 1888. Serial No. 283,498. (No model.)

To all whom it may concern:

Be it known that I, WILLIAM H. JENKINS, residing in Philadelphia, in the county of Philadelphia and State of Pennsylvania, have 5 invented certain new and useful Improvements in Mining-Drills, of which the following is a specification.

My invention relates to mining-drills, and it refers more particularly to a patent for mining-drills granted to me February 9, 1886, No. 335,591; and it consists in the novel construction and combination of parts, as will be hereinafter fully described in the annexed specification and particularly pointed out in the 5 claims, reference being had to the accompanying drawings, in which—

Figure 1 is a side view of my improved drill, showing the drill mechanism in a vertical position. Fig. 2 is a front or face view of the 20 drill-carrying frame, parts being broken away. Fig. 3 is a top plan view of the same, parts being broken away. Fig. 4 is a central vertical section taken on line 4 4, Figs. 3 and 2. Fig. 5 is a detail view illustrating the 25 drill-operating cam. Fig. 6 is a horizontal section on the line 6 6; and Figs. 7, 7^a, and 7^b are detail views of the connecting-disks.

In the accompanying drawings, A denotes a movable frame, in which is mounted the 30 drill-rod B and the drill-operating mechanism.

To extensions A' A' of the frame A are secured stationary slideways C C, in which is arranged to travel a cross-head, D. The cross-head D is formed in two sections, C' C', which 35 are provided at their lower interior faces each with a semicircular recess, c c, having enlarged head portions c' c', which recesses embrace the upper stem, e, of the drill-rod B, which is provided with a head, e', which fits 40 into the portions c' c', as shown. The slideways C are formed with V-shaped grooves d in the direction of their length, in which fit to slide therein V projections c³ c³, formed on the edges of the cross-head section C'. Upon 45 the outer face of the cross-head D is secured a U-shaped metal frame, F, the arms d⁴ d⁴ of which extend inwardly and embrace the stationary slideways C C, and it is provided with a downwardly-projecting portion, d', as shown. 50 The frame F is bolted to the cross-head by the bolts b b and the pin X.

G denotes the crank-shaft, which is journaled in the frame A, provided upon its outer end with a suitable crank-handle, g, and upon its inner end it is connected with a hollow 55 disk, H, into which is rigidly fixed the cam I, the specific construction and operation of which will be hereinafter explained.

The angular extensions or arms d¹ d¹ of the frame F are provided with cam-shaped openings J J, formed of the straight portions j j' and the inclines j² j², formed at their diagonal upper and lower edges with semicircular seats j³ j⁴. By reference to the drawings it will be seen that the openings J in the arms 65 d¹ d¹ are arranged in contra positions—i. e., the incline portion of one extends from the upper front edge of the straight portion j downward to the lower inner edge of the rear straight portion, j', while in the opposite arm 70 the short straight portion j of the opening is at the rear edge of the arm and the incline extending from such rear edge toward the front edge. The purpose of such construction will presently be described. 75

K K represent two levers, which are centrally pivoted to the fixed ways C C—one on the outer face of each of the said ways C—and have their upper ends extended and provided with roller-bearings which engage the 80 openings in the arms d⁴ d⁴, their lower ends being extended at k k, which ends are arranged to automatically operate upon the chuck L, secured to the drill-rod. These levers normally rest with their upper ends in 85 the upper semicircular seats, j³, and are held in such positions by stout flat springs l l'. By reference to the drawings it will be observed that the said levers are arranged cross-wise in relation to each other, and that the 90 spring l presses against the lower extended portion, k, of one of the levers and forces the upper end outward, while the spring l' presses against the upper end, k', of the opposite lever, and thus throws said end inward. 95

The drill-rod B is operated by means of the cam and the spring M. The operating-spring M is what is known as a "U-spring," and it is arranged with its inner leaf, m, between the ends 11 of the frame A, which end extends 100 forward of said ends and rests upon the cross-head before referred to, while its leaf m' ex-

tends outside the frame and over in line with the leaf m , and is fitted over a screw-rod, m^3 , projecting from an extension, 2, of the frame, said screw-rod being provided with a thumb-nut, N , which bears against the leaf m' , and by means of which the tension of said spring may be regulated. The leaf m , as before stated, extends over and presses against the cross-head, and such leaf is applied against a 10 knife-edge center bearing-plate, O , which is secured in recesses o , formed in the upper ends of the cross-head plates $C' C'$. By adjusting the leaf m in the manner described the greatest possible range is given to the tension, 15 friction is reduced to the minimum, and the altering and changing of the spring are accomplished with ease without otherwise disturbing the machine—a result which could not be accomplished by arranging the operating-spring in the manner shown in my previous 20 patent referred to.

The drill-chuck L , which is screwed on the lower end of the drill-rod B , consists of the hub L' and the enlarged head L^2 , provided 25 with a series of radial projections, L^3 , formed with beveled portions l^3 on their inner edges.

The peculiar construction of the several parts just described—*i. e.*, the spring, the cross-head, frame F , the arms K K , and the 30 chuck L —are so arranged as to accomplish the rotation of the drill in a manner which I will now describe.

In the patent granted to me, No. 335,591, it will be observed that the drill-rod was operated by the cam and pin, and the spiral spring, and the rotation of the chuck was caused by a cam-arm attached to the cross-head, which operated upon the chuck when it was on its upward movement, and thereby caused the 40 same to rotate. This form of device, after some experience, was found to be defective, inasmuch as the proper rotation of the chuck was not always accomplished. The chuck was sometimes turned too much, and no positive movement of the same was thereby obtained. By the construction described in the 45 present case the rotation of the drill-chuck is positively accomplished, inasmuch as each blow of the drill-rod operates the chuck a certain degree, and no more or less movement 50 can be communicated to said chuck at each movement of the drill-rod; hence the said rotary movement to the chuck and drill will therefore be always regular.

55 The rotary movement to the chuck L is accomplished as follows: The chuck being at its lowest position, the cross-head and pin also at that down or under position, power is then applied to crank-shaft, and the cam will begin to act upon the pin X and start to raise the cross-head and the frame F . As the cross-head begins to rise, the chuck will be lifted to be disengaged from a stop, P , connected to the frame A , (in a manner as will be presently explained,) and before it is entirely disengaged from said stop P the head L' will engage with two of its radial projections

with the lower ends of the arms K , said arms connecting with said head L' at opposite sides of the center of motion of said chucks, as clearly shown in the drawings. A slightly further rise of the cross-head will entirely release the chuck from the stop P . At this time it will be observed that the roller-bearing upper ends of the arms K will now be at the beginning of the inclines in the openings J in the said arms d of the frame F , and a still further movement of the cross-head and the frame F will cause the inclines to operate the arms and swing them laterally until the roller-bearings reach the semicircular seats in the lower edges of the openings J in the arms. The said openings J in the frame and their relation to the operating-crank and pin are such that when the cam drops the pin X the roller-bearing will be at the lowest or inner ends of the openings J , and such movement of the arms K is of a degree sufficient to turn the chuck one projection or tooth, the roller-bearings of the arms at this time resting 90 against the long straight portions of the openings J will thereby prevent said arms K from further movement, and thus hold the chuck in such rotated position. Now, as the tension of the spring will be immediately applied as 95 soon as the cam drops the pin X , the said cross-head will be so quickly shot forward that the roller-bearing ends of the arms will tend to bear against the long straight sides of the opening J , and the chuck before it 100 leaves the ends k of the arms K will have engaged with the stop P , and the portions k of the arms being then entirely released from contact with the chuck, the tension of the flat springs $l^1 l^2$ will cause the upper ends of 105 said roller-bearing ends to again assume their normal positions. Thus it will be seen that the chuck, after it has reached its upper movement and has been rotated to the degree described, when the cross-head is 110 acted upon by the spring, and will descend in a perfectly straight line, which is a great desideratum in mining-drills. The stop P , previously referred to, which engages the chuck, is a pivotal one, and consists in pivoting a bent arm, Q , as at g , to the frame A , its forward end, P , being arranged to project in line of the radial projections on the chuck L , and its opposite arm is formed with an upward extension, Q' , which is provided with a lock, 115 which may be a bayonet or other similar joint, which connects said arm with a short stud, 4, on the frame A , by means of which the said arm Q' may be readily disengaged from the stud 4 and the stop P thrown out of engagement with the chuck, as shown in dotted lines, Fig. 1. By thus arranging the stop it will be noticed that the chuck may thereby be turned in either way when it is desired to make any 120 change in the drills, or for other obvious purposes.

Near the lower end of the cross-head I provide the drill-rod B with a collar, B' , and upon the extensions 5 5 of the frame A , I form a

cushion device, R, which consists of a disk, r , fitted over the drill-rod B, and vertical circular metal rings, r' , is fitted upon said disk. Placed around the drill-rod B, and arranged to 5 rest between the rings r' are a series of circular split rubber rings, r^2 r^3 . By forming the cushion in this manner it will be seen that the split rubber rings r^2 may be changed or their number increased or decreased without taking 10 apart any portion of the mechanism, said device forming a cushion against which the rod strikes, and especially protects the jar of said rod when the drill strikes a "seam" in the rock.

15 Upon one side the frame A is provided with a yoke portion, A', which is provided with a longitudinal dovetail opening, A², into which is fitted a dovetail guide, S, which is integrally formed with the main frame T, which is braced 20 within the mine, and which supports the drill mechanism frame A. The yoke A' is also provided with a longitudinal screw-threaded opening, A⁴, in which is fitted the feed-screw U, which is passed through the arm T' of the 25 frame T and held to said arm by the collars t t', and having at its outer end a suitable hand-wheel, f, by the turning of which the drill-frame A is fed forward with the drill.

The main supporting-frame T consists of 30 the arms T' and T², which are connected with the dovetail guide S, the arm T² having a pivotal connection upon a bolt connected with a supplemental portion, T⁴, of the frame T, the other arm, T', having a pivotal connection 35 with a U-shaped arm, V, which is connected at its end v with said arm T' and at its opposite end v' with the supplemental frame T⁴ in a manner presently described.

The supplemental frame T⁴, which is arranged to support the weight of the entire apparatus and to receive the shock, is provided at one end, T⁵, with an adjustable arm, W, which is connected to the said end T⁵ by means of the bolt w, passing through ears w' of a plate, w², and the end T⁵, which plate has fixed thereto the screw-rod w³, upon which the arm W is adjusted, by means of which the forward end of said frame T⁴ is securely braced to the sides of the mine. The opposite end of said frame portion T⁴ is connected to the column Z and held thereto in such a manner that the same may have an approximately universal motion in relation thereto. The specific construction whereby such result 55 is obtained will presently be explained. It will, however, be readily understood that when said frame is placed in a desired relation to the column the same is securely fixed in such position and the forward end braced by the adjustable arm W, the V-shaped arm being also held in a fixed position.

As before stated, the main frame T is pivoted upon the supplemental frame T⁴, which connection forms practically a hinged connection. This feature forms an important part of my invention, inasmuch as by such arrangement I can at any time swing the main

frame, which carries the entire drill mechanism, away from the hole drilled when it is desired to "spoon" out the pulverized rock, or 70 when it is necessary to change the drill-bits, or for any other purpose, and when said frame is swung back the same will again resume its place without the slightest deviation from its previous position. To secure said frame T 75 in such position with the supplemental portion T⁴, and yet provide means of easily disconnecting the same, I construct it in a manner which I will now proceed to describe. The forward end of the arm T² is formed with a reduced extension, T⁶, which is of dovetail form in cross-section, and upon the frame T⁴, at its forward end, I form a projecting portion, T⁷, which fits in the reduced part of the arm T², and is of a similar shape in cross-section as the extension T⁶, the two forming 85 a hexagon shape in cross-section when united.

Upon the outer edges of the arm T² are formed guide-ribs 10, between which fits and slides a U-shaped bent spring, 11, the forward ends, 12, of which are formed to snugly fit the outer hexagonal portion of the frame-arms T² and T⁴, and thereby hold the same in position together. To secure them in such position, I provide the arm T² with an elongated slot, 13, through which and the leaves 14 14 of the spring 11 is passed a bolt, 15, provided with a nut, 16^a, by the adjustment of which nut the leaves may be securely held against said arm T², and thereby hold the 100 parts T² and T⁴ together. If, however, the nut is loosened on the bolt, the said leaves will expand, (see Fig. 6,) in which case the spring and bolt may be moved back, the bolt working in the elongated slot until the front 105 ends of the spring will be disengaged from the ends of the arms T² and T⁴, and thereby permit the main frame and drill mechanism to be swung on their pivots.

As before stated, the supplemental portion T⁴ of the frame T is connected to the column Z in such a manner as to form an approximately universal joint, the construction of which is clearly illustrated in Fig. 6 of the drawings. By reference to said figure it will 110 be seen that I form the inner edge of the arm T⁴ with a disk, 16, which is provided with a series of circular V-shaped projections, 17, which engage with similar V-shaped grooves, 18, formed in the inner face, 19, of a disk, 20, which is formed integral with and at the lower end of the U-shaped arm V, and which disk is also provided on its outer face with V-shaped grooves 21, which engage V-shaped projections on the inner face of the horizontal portion 22 of an angle-plate, 23, and through said angle-plate 23, disks 16 and 20, and the arm T is passed a bolt, 25, formed with a collar, 24, entered into a socket, 26, in the arm T⁴. Said bolt is also provided with a reduced portion, 27, upon which is pivoted the arm T², as shown. By this arrangement 120 it will be seen that by tightening the nut 28 the disks 16 and 20 will be secured, and by 125 130

- adjusting the nut 29 the arm T² also held in position. Upon the vertical portion 30 of the angle-plate 23 V-shaped circular grooves 32 are provided, meshing with similar grooves 33 formed on an angle-plate, 33, said plates 23 and 33 being held in adjustment by means of the bolt 36 and nut 37, as clearly shown in the drawings. The angle-plate 33 is provided with a portion, 34, which extends vertically 10 but at right angles to the part 33, which is provided with V-shaped projections engaging a disk, 38, having similar grooves, 39, engaging the angle-plate projections, said disk 38 being provided upon its inner face with lateral ribs 40, between which is fitted the front end of a connecting-bar, 41, a nutted bolt, 42, passing through said bar, disk 38, and angle-plate, and thus securing said parts together. The connecting-bar 41 extends back 15 to and is journaled on the column Z in any well-known manner, and through its extended end 43 is passed an adjustable brace-bar, 44, by means of which and the adjustable brace-arm W, previously described, the apparatus is 20 securely braced in relation to the mine-walls.
- From the foregoing it will be seen that by connecting the frame to the column Z in the manner described the frame may have various adjustments. By means of the disk 31 the frame has a movement back and forward in the direction of the length of the connecting-bar, while by means of the disk 23 and its adjustment the frame will have a movement back and forth at right 25 angles to the connecting-bar, and through the medium of the disk 16 and its adjustments the frame will have a movement back and forth horizontally to the other movements described. This manner of adjusting 30 the frame, as far as I know, has never been accomplished, and it is found by experience that by such connection every movement of the drill-frame necessary in drilling may be obtained.
- 40 By reference to Fig. 5 of the drawings the specific construction of the cam I is clearly set forth, and which I will now proceed to describe, previous to which I will refer somewhat to the construction of the cam device 45 shown in my previous patent, No. 335,591, and thereby point out more particularly wherein my improved construction of cam differs from the same.
- In the construction of the cam in my previous patent it will be seen that at each revolution of the cam the drill-rod is lifted twice, and by arranging the cam portions with their straight faces in diametrically-coincident planes that it is necessary to make the pin in 50 a semicircular form to permit it to operate in said cam-faces. In the practical application of the cam described I have found that when the spring-tension was of a degree to strike but a moderate blow the revolution of the 55 cam-disk would bring the lower or beginning portion of the cam-groove under the pin before the rod would have reached its lowest

point of thrust, and by arranging the cam-curve in the manner described it would have its bearing-surface too near the horizontal diameter, thereby decreasing the leverage of the cam upon the pin and greatly increasing the friction, as the leverage upon said pin was nearer to a sidewise than a vertical pressure. I have found by practical experience that 75 the cam illustrated in Fig. 5 will avoid all of said objections.

The cam I consists of a solid piece of steel securely fitted to the disk H and extending beyond the rim of said disk to a distance of 80 about one-half its thickness. In this plate I form but a single cam-recess or operating-groove, I', the heel or straight portion I² of which is arranged a short distance to one side of the center of the cam. The beginning or 85 point I³ of the curved portion of said groove commences at a point in the cam-periphery of a distance sufficient to permit of the positive fall of the pin X before said point I³ can turn under it. It will be observed that by extending the straight portion of the cam-groove to one side or the center of said cam I add distance between the heel and point of said groove without the necessity of increasing the curvature of the curved portion of the groove, 90 and thus avoid additional friction, as each degree of additional curvature to said portion proportionately increases the friction. The curved portion I³ is formed of a compound curve, which rises toward and extends over 95 the center of said cam-face, gradually diminishing its radial distance from the center, and extending to a distance below said center, and merged into the straight or heel portion, as clearly shown in the drawings. 100 By arranging the cam in this manner it will be observed that but one blow of the drill-rod will be accomplished at each complete revolution of the cam. It will also be readily understood that by the formation of the cam-groove as 105 described, as the pin X continues to rise, the leverage upon said pin will gradually increase, thereby compensating for the additional tension upon the spring.

A still further advantage of forming the 110 heel portion to one side of the central line of the cam is that the pin X can be made of considerably more strength, inasmuch as its straight surface is extended beyond the center and in line with the heel portion, as shown. It 115 will also be observed that by the peculiar formation of the cam-groove the curved portion will lift the pin from its under side and apply its pressure almost in a vertical line, and thereby avoid the side pressure which is encountered in the operation of the cam and pin 120 shown in my previous patent referred to. This vertical pressure upon the pin is continued through the entire lift of the pin while the cam is being rotated.

130 From the foregoing description, taken in connection with the drawings, the operation and advantages of my improved drill will be readily understood. It will be seen that a

drill of great capacity is produced, the mechanism for operating the drill being of such a character as to adapt the same to all classes and conditions of rock, and by the various means of adjustment the same may readily be set for operation at any position desired in drilling.

Having thus described my invention, what I claim, and desire to secure by Letters Patent, 10 is—

1. The combination, with a drill-rod having a lifting-pin, of a cam for operating the same, said cam consisting of a disk provided with groove or cut-away portion I', having a radial 15 side arranged at one side of the center line of said cam-disk, said radial portion ending short of the center of the disk, and a curved side beginning with its point at the opposite side of the said center line, extending from 20 the periphery toward the center, having a gradually-decreasing radius, said curvature extending over and past the center of said cam-disk and ending at the inner end of the radial portion, substantially as and for the 25 purpose described.

2. The combination, with a cam provided with a cam-groove, I, substantially as shown, one edge of which is formed of a radial straight portion arranged to one side of the 30 center of the cam, of a spring-actuated drill-rod having a lifting-pin formed with an approximately semicircular bearing-face for operation in said groove, and its opposite face formed straight and extended beyond the 35 center of the cam, whereby the pin shall be instantly released by the cam when the said straight portion of the pin and the radial straight side of the groove shall be in coincident planes, substantially as and for the purposes set forth.

3. In a mining-drill, the combination of the drill-supporting frame and the columns Z, for supporting said frame, of a series of adjustable friction-disks connecting said frame to 45 the column, said disks consisting of a horizontal disk, 20, adjustably secured to the drill-supporting frame, provided with a vertical portion, 30, having a central pivot bolt, an angle-plate, 33, adjustably secured upon 50 said plate in frictional contact with the portion 30, said plate provided with vertical portion 34 at right angles to the part 33, a disk, 38, secured upon an arm connected with the column Z, and a pivotal bolt passing centrally 55 through said portion 34 and the disk 38, each of said disk portions having independent adjustments, substantially as shown and described.

4. In a mining-drill, the combination, with 60 the main frame, a series of adjustable disks formed thereon, as shown and described, and the column Z, of the bar 41, mounted on the column Z and connected at one end with the adjustable disks, provided with an extended 65 portion, 43, an adjustable brace-bar, 44, journaled in the portion 43, and the adjustable brace-bar W, connected to the front end of the

main frame, whereby said frame is securely adjusted to the main walls, substantially as shown and described.

5. In a mining-drill, the combination, with the cam I, journaled in the frame A, fixed guides C' C', secured in said frame, provided with V-shaped grooves, the cross-head having V-shaped tongues entered in said grooves, and a lifting-pin connecting said cross-head and cam, of the U-shaped spring resting against the upper edge of the cross-head, and its opposite end connected with the frame A, substantially as and for the purpose described.

6. The combination, with the cross-head, and the U-shaped spring M, for operating the forward throw of said cross-head, one leaf of said spring connected with and adjustably secured to the frame, the other leaf extending over the cross-head, of the central bearing-plate secured in the upper end of the cross-head and provided with a knife-bearing edge adapted to support the leaf m of the spring M, substantially as and for the purpose described.

7. The combination, with the cross-head D, the drill-rod B, secured thereto, a chuck, L, provided with radial projections secured to said drill-rod, and the cam for operating the drill-rod and cross-head, said cross-head formed with cam-recesses in its opposite ends, of the arms K, pivoted to the frame and disposed one to each end of the cross-head D, the upper ends thereof engaging the said cam-recesses, 100 their lower ends engaging the radial projections on the chuck L, said arms adapted to oscillate by the travel of the cross-head, whereby a rotary motion is imparted to the chuck, substantially as and for the purposes 105 shown and described.

8. In a mining-drill, the combination, with the cross-head D, the frame E, secured thereto, having lateral arms d⁴ d⁴ formed thereon, said arms provided with cam-shaped openings J, arranged in contrarelation to each other, the drill-rod B, connected with the cross-head, and the chuck L, connected to the drill-rod, said chuck provided with radial projections, of the swinging arms K, centrally pivoted 110 to the frame A, and disposed one to the outer face of each of the said arms d⁴, connected at their upper ends with the cam-openings J, their lower ends, K, arranged to engage the radial projections on the chuck, said arms 115 adapted to be oscillated by the travel of the cross-head and the cam mechanism for operating the cross-head, substantially as shown and described, as and for the purpose set forth.

9. In a mining-drill, the combination, with the cross-head, the frame F, secured thereto, having arms d⁴ d⁴ projecting therefrom over the sides of the cross-head, said arms provided with cam-shaped openings arranged in contrarelation to each other, the drill-rod B, 130 secured to the cross-head, and the chuck L, secured to the drill-rod, provided with radial projections, of the arms K, centrally pivoted upon the sides of the frame, said arms pro-

vided at their upper ends with roller-bearings engaging the cam-openings *J* in the arms *d*⁴, their lower ends, *k*, arranged to engage the radial projections, the chuck-springs *Z Z'*, for automatically throwing said arms back to their normal positions, and the cam mechanism, substantially as described and shown, for operating the cross-head, all arranged as and for the purpose described.

10. The combination, with the cross-head carrying the drill-rod, the chuck attached to the said drill-rod, the cam mechanism *I*, substantially as shown and described, for operating the upward movement of the cross-head, and the spring for forcing said cross-head down, of the arms centrally pivoted, said arms arranged to oscillate by contact at their upper ends with cam-faces of the cross-head, their lower ends adapted to engage the chuck 15 and revolve the same when said arms are oscillated, substantially as shown and described.

11. In a mining-drill, the combination, with the drill-rod and the chuck secured thereto, 25 provided with radial projections, of the pivotal stop *P*, said stop adapted to engage the said radial projections, said stop having an extension, *Q'*, provided with a bayonet or other lock joint engaging a stud upon the frame, whereby said stop may be swung out 30 of engagement with said stud and permit of the rotation of said drill-chuck, substantially as and for the purpose specified.

12. In a mining-drill, the combination of the

main frame provided with a **U**-shaped arm, 35 *V*, forward-extended arms *T'* and *T*², and a supplemental arm, *T*⁴, the arms *T'* and *T*⁴ supporting the drill-frame, said arm *T'* pivoted to the outer end of the arm *V*, and the arm *T*² pivoted upon the bolt connecting said arm *V* 40 with the arm *T*⁴, said connections of arms *T'* *T*² permitting the swinging of the frame *T* and the drill mechanism away from its working position, substantially as shown and described.

13. In a mining-drill, the combination, with 45 the main frame *T*, said frame consisting of the arms *T'* *T*² and **U**-shaped arm *V*, and the supplemental portion *T*⁴, said arms having hinged connections at their outer ends to the arm *V* and part *T*, respectively, the forward 50 end of the arm *T*² formed with a reduced portion dovetailed in cross-section, and the arm *T*⁴ having an enlarged portion arranged to fit the reduced part of the arm *T*², said arm provided with an elongated slot, of the **U**-spring embracing the arm *T*², its forward end adapted to embrace the ends of the arms *T'* *T*⁴, and an adjusting-bolt passed through the spring-arms and the slot, by the adjustment of which the said spring may be slid back and permit the 60 arms *T'* and *T*⁴ to become disconnected, thereby allowing the frame to be swung upon its pivots, substantially as shown and described. 55
